UNITED STATES PATENT OFFICE.

JAMES M. EIFFE, OF FULTONVILLE, NEW YORK, ASSIGNOR TO WHITE MOP WRINGER COMPANY, OF FULTONVILLE, NEW YORK, A CORPORATION OF NEW YORK.

MOPSTICK.

Application filed December 8, 1923. Serial No. 679,350.

To all whom it may concern:

Be it known that I, JAMES M. EIFFE, citizen of the United States, residing at Fultonville, county of Montgomery, State of New York, have invented a certain new and useful Improvement in Mopsticks, and declare the following to be a full, clear, and exact description of the same, such as will enable others skilled in the art to which it pertains 10 to make and use the same, reference being had to the accompanying drawings, which form a part of this specification.

My invention relates to mop sticks shown in the accompanying drawings and more particularly described in the following specification and claims.

The object of my invention is to provide a simple and inexpensively constructed mop stick formed of metal, of rigid construction 20 and not apt to get out of order or become broken through use.

A further object of my invention is to provide a construction which will be relatively light and easy to handle and which will securely grip the mop, the arrangement being such that the mop when in use will overlap the metal supporting portion of the device so as to protect furniture or the wainscoting 25 of a room from injury.

30 A further object of the invention is to provide means for readily adjusting the device for mops of different thicknesses, whereby the latter may be securely held regardless of the size or thickness of the mop.

35 A further object of the invention is to provide simple and effective means for securing the mop to the head of the stick, which may be easily released when it is desired to remove the mop for replacement.

40 With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying the specification:—

50 Figure 1 is a side elevation of the device, showing a portion of a mop, with parts broken away,—whereby the head may be shown on a relatively large scale,

Figure 2 is a longitudinal sectional view 55 through the same showing in dotted lines the mop-chain fitting for securing the mop to the head,—as when removing or replacing the mop.

Figure 3 is a cross-sectional view through 60 the clamping collar, whereby the fitting attached to the end of the chain is secured to the handle to hold the mop upon the head of the latter.

Figure 4 is a detail sectional view through 65 a portion of the mop head, showing the hook-shaped member engaging the opposite end of the chain as when released from the head for adjusting the chain for mops of varying thicknesses.

Figure 5 is a detail sectional view taken on or about line 5—5 of Figure 2, showing the channel-shaped end of the mop handle to which the mop is held by the engaging chain.

70 Referring now to the letters of reference placed upon the drawings:—

A, denotes a handle formed of tubing divided longitudinally at one end as at A¹ that it may be bent outwardly to form a 80 head A²,—the laterally extending channel-shaped ends of which overlap that they may be riveted together as at A³.

B, indicates a yoke-shaped clip adapted to overlap one of the arms A⁴ forming the head 85 of the mop stick, the edges being bent back as at B¹ to overlap the edges of one of the arms A⁴. B² designates a hook integral with the clip, adapted to enter any one of a series of apertures A^a in the arm A⁴, for purposes 90 of adjustment.

C, represents a chain secured to the clip B extending laterally across the head to secure the mop D in position.

E, denotes a fitting, secured to the free 95 end of the chain, of arc-shaped form in cross-section to conform to the contour of the stick and its spreading arm. E¹, E¹, indicate hooks integral with the fitting E adapted to project through suitable slots a 100 formed in the spreading arm A⁴ of the stick to assist in locking the chain in position.

F, designates a suitable rotatable clamping collar sleeved on the handle A, having a projecting overlapping portion F¹, provided with ribs f adapted to enter grooves e formed on the end of the fitting E to lock the latter adjacent to the handle, as clearly

indicated in Figure 2. F^2 represents a thumb-piece to facilitate the rotation of the collar F .

G , denotes a lug or stud secured to the handle to maintain the rotatable collar upon the handle in convenient position to receive the end of the fitting. The handle at its upper end is preferably given an arc-shape formation as at A^b that it may be conveniently gripped by the hand of the operator.

Having indicated the several parts by reference letters the construction and operation of the device will be readily understood.

15 The yoke-shaped clip B is first adjusted upon the spreading arm of the handle and secured by engaging its hook in one of the apertures therein that it may be adapted for the thickness of the mop, the chain is 20 then extended through the mop and the fitting E attached to its free end is then secured to the opposite spreading arm of the handle upon engaging the hooks E^1 through the slots provided in the arm. The end of 25 the fitting E is then forced adjacent to the handle and the clamping collar F rotated so as to overlap and engage the end of the fitting;—the mop being thus securely held in place. To release the mop from the end 30 of the stick, the collar F is rotated so as to free the fitting E , when the mop may be removed as will be readily understood.

Having thus described my invention what I claim is:

35 1. In a device of the character described, a tubular handle longitudinally divided at one end, said divided portions being bent in opposite directions at an angle to the handle with their ends bent laterally toward each 40 other at right angles to the handle; means securing said ends together; a chain for clamping a mop against the laterally extending divided portions of the handle; means for adjustably securing one end of 45 the chain to one of the divided portions of the handle; a fitting secured to the other end of the chain adapted to overlap the other divided angularly extending portion of the handle, and means for engaging the 50 fitting to the handle, whereby the mop may be secured to the laterally extending right-angle portions of the divided handle.

2. In a device of the character described; a tubular handle longitudinally divided at 55 one end, said divided portions being bent in opposite directions at an angle to the handle; their ends being bent laterally toward each other at right-angles to the handle; means securing said ends together; a chain for clamping a mop against the laterally extended divided portions of the handle; an 60 adjustable clip secured to one end of the chain provided with a hook adapted to enter a plurality of apertures provided in one of the divided portions of the handle; a fitting 65 the divided portions of the handle; a fitting

secured to the other end of the chain having hooks adapted to enter slots provided in the other divided portion of the handle, and means sleeved upon the handle adapted to engage the fitting, whereby the mop may be 70 secured to the laterally extended right-angle portions of the divided handle.

3. In a device of the character described, a tubular handle, longitudinally divided at one end, said divided portions being bent in 75 opposite directions at an angle to the handle, their ends being bent laterally toward each other at right-angles to the handle, said right-angle portions forming a channel in cross-section; means securing said channel-shaped ends together; a chain for clamping a mop against the laterally extended channel portions of the handle; an 80 adjustable clip secured to one end of the chain, provided with a hook adapted to enter a plurality of apertures provided in one of the divided portions of the handle; a fitting secured to the other end of the chain having hooks adapted to enter slots provided in the other divided portion of the handle and a rotatable collar sleeved upon the handle having a portion adapted to overlap the end of the fitting, said overlapping portion of the collar having a rib 85 adapted to enter a groove formed in the end of the fitting.

4. In a device of the character described, a tubular handle, longitudinally divided at one end, said divided portions being bent in opposite directions at an angle to the handle, 100 their ends being bent laterally toward each other at right-angles to the handle, said right-angle portions forming a channel in cross-section; means securing said channel-shaped ends together; a chain for clamping a mop against the laterally extended channel portions of the handle; an adjustable clip secured to one end of the chain provided with a hook adapted to enter a plurality of apertures provided in one of the 105 divided portions of the handle; a fitting secured to the other end of the chain having hooks adapted to enter slots provided in the other divided portion of the handle; a rotatable collar sleeved upon the handle having a portion overlapping the end of the fitting provided with a rib adapted to enter a groove formed in the end of the fitting, and a lug projecting from the handle adapted to 110 maintain said collar in position to engage the end of the fitting.

5. In a device of the character described, a tubular handle, longitudinally divided at one end, said divided portions being bent in opposite directions at an angle to the handle, 115 their ends being bent laterally toward each other at right-angles to the handle, said right-angle portions forming a channel in cross-section; means securing said channel-shaped ends together; a chain for clamping 120

- a mop against the laterally extended channel portion of the handle; an adjustable clip secured to one end of the chain, provided with a hook adapted to enter a plurality of apertures provided in one of the divided portions of the handle; a fitting secured to the other end of the chain having hooks adapted to enter slots provided in the other divided portion of the handle 10 and a rotatable collar sleeved upon the handle having a portion adapted to overlap the end of the fitting provided with a rib adapted to enter a groove formed in the end of the fitting, said collar also provided 15 with a projecting thumb-piece to facilitate its rotation upon the handle.
6. In a device of the character described, a tubular handle longitudinally divided at one end, said divided portions being bent in opposite directions at an angle to the handle 20 with their ends extending laterally toward each other at right-angles to the handle, the
- opposite end of said tubular handle having its edge bent inwardly to provide an arc-shaped end for convenience in handling; 25 means securing the divided ends of said handle together; a chain for clamping a mop against the laterally extending divided portions of the handle; means for adjustably securing one end of the chain to one of the divided portions of the handle; a fitting secured to the other end of the chain adapted 30 to overlap the other divided angularly extending portion of the handle, and means for engaging the fitting to the handle, 35 whereby the mop may be secured to the laterally extending right-angle portion of the divided handle.

In testimony wherof, I sign this specification in the presence of two witnesses.
